Patented May 14, 1912.

UNITED STATES PATENT OFFICE.

THOMAS G. PLANT, OF BOSTON, MASSACHUSETTS, ASSIGNOR TO UNITED SHOE MACHINERY COMPANY, OF BOSTON, MASSACHUSETTS, A CORPORATION OF NEW JERSEY.

SOLE-EDGE PROTECTOR FOR BOOTS OR SHOES.

1,026,048.

Specification of Letters Patent.

Patented May 14, 1912.

Application filed February 19, 1909. Serial No. 478,952.

To all whom it may concern:

Be it known that I, THOMAS G. PLANT, a citizen of the United States, residing at Boston, in the county of Suffolk and State 5 of Massachusetts, have invented an Improvement in Sole-Edge Protectors for Boots or Shoes, of which the following description, in connection with the accompanying drawing, is a specification, like reference characters on the drawing representing like parts.

In the manufacture of boots and shoes the uppers usually become more or less soiled with wax and dirt, which must be removed before the shoes are shipped. The materials 15 and work of removing this dirt and wax or in otherwise cleaning or finishing the uppers, either on the treeing machine or otherwise, is found to mar the finish of the edges of the soles, and since these edges practically 20 cannot conveniently be refinished, it is necessary to ship the shoes in a more or less damaged condition.

My invention aims to provide means for protecting the sole edges when once they are 25 wheeled and set from subsequent damage during the further cleaning or other processes to which the shoes are subjected.

The accompanying drawing illustrates one embodiment of my invention, wherein— 30 Figure 1 is a view looking at the bottom of a shoe provided with protection means illustrating one embodiment of my invention; Fig. 2, a view of the protection means from the opposite face to Fig. 1; Fig. 3, a 35 transverse sectional detail illustrating the engagement of the protection means with the forepart sole edge; and Fig. 4, a sectional detail illustrating a preferred arrangement for protecting the heel rand or 40 heel portion of the sole.

Referring to the drawing, the sole of the shoe is indicated at S, the shank portion thereof at S' and the heel at H, a portion of the upper being indicated at U (Figs. 3 and 45 4). The extent of the sole around the forepart is best shown at S² (Fig. 3), the sole edge as here used including that portion of the welt to which it is attached in the usual manner.

50 Among the later processes of shoe making, though not the final process to which the shoe is subjected, the outer edge or perimeter of the sole along the shank and about the forepart is finished or "set," and either

before or after the setting of the edge the marginal portion of the sole that projects beyond the upper, is also finished, usually by "wheeling," "stitch separating" or the like.

It should be understood that in referring 60 to a welt shoe the term "sole edge," as commonly used, includes not only the edge or marginal portion of the outsole but also that portion of the welt projecting beyond the upper to which the outsole is secured.

To protect the sole edge so set and wheeled or otherwise finished, my present invention comprehends a pliable and it may be textile shield 1 adapted to encircle the forepart sole edge and embrace more or less the top 70 and bottom edge faces thereof. In the present embodiment of my invention, this edge shield is shown as a part of a bag like member 2, which is stretched over the bottom of the sole and preferably has an aperture near 75 the central portion of the sole, the edge of the shield about this aperture being gathered about an elastic or other contractile device or member 3, which acts to draw the edge shield always closely to and about the 80 sole edge.

To cover in whole or in part the top face of the sole extension—that is to say, the wheeled or separated face of the sole—the shield 1 is formed to overlie such face to 85 any desired extent, as indicated at 4 (Fig. 3). For the purpose of drawing this overlying face portion 4 toward or into the crease between the upper and sole edge, I have provided such overturned portion 4 90 with a draw wire or member 5 which, when contracted, will serve to draw the edge of the shield closely down to the bottom of the crease. To permit this wire drawn edge to draw into any inequalities or depressions in 95 the bottom of the crease independently of a portion which overlies the sole edge, I have interposed an elastic member 6 between the margin of the shield 4 and that portion which embraces the wire which permits the 100 latter closely to adapt itself to the bottom of the crease without requiring a corresponding change of contour in the edge portion 1. Thus the elastic 3 upon the bottom of the sole draws the shield tightly to the 105 edge from the bottom face of the sole, while the wire may be employed to draw the shield closely into the bottom of the crease,

the two coöperating to insure close contact of the shield 1 about the sole edge and covering so much of the top and bottom edge faces thereof as may be desired to protect 5 the sole from damage during cleaning of the upper or other processes to which the shoe may be subjected after the sole has been set and wheeled.

To retain the shield in position, I may 10 employ any suitable means, conveniently a pair of resilient or elastic members 7 (Fig. 1) engaging the hooked ends of the wire 5 and at their opposite ends engaging the looped or otherwise suitably formed ends of 15 a heel or rand shield 8 (see Fig. 4). This rand shield is preferably made of celluloid, metal or any suitable material that will conform approximately at least to the upper portion of the heel and cover so much of 20 the face thereof as may be desired or necessary, the same being provided at its upper edge with an inturned, notched lip 9 to overlie the rand or extend about the heel. This overlying lip retains the shield 8 in 25 position and at the same time protects the heel finish thereunder.

It will be observed that the tension of the elastic member 7 operates to hold both the forepart and the heel shields in position and 30 under constant tension, yet they may be readily removed by drawing either one sufficiently toward its corresponding end of the shoe to release it, and thereby permit ready removal of the other.

35 In applying the device, it will be convenient first to slip the forepart over and about the sole edge around the forepart and then stretch the heel shield rearward and give it a half turn to cross the elastic members 7, when it may be slipped into position upon the heel, the elastic members contracting to retain both shields in position.

To facilitate placing the forepart shield upon the sole and at the same time to afford 45 additional protection to the sole edge at any desired point or points, I may employ a non-pliable shield 9^a which may be of hard rubber, celluloid or metal, preferably cemented or otherwise secured to the textile member 2, and shaped approximately to 50 correspond with the contour of the sole and constructed to present top and bottom overlying portions 10 and 11 to embrace and cover more or less the top and bottom edge 55 faces of the sole. That portion 11 which overlies the bottom of the sole is preferably of substantial width, as indicated in Figs. 1 and 2, and is provided with reëntrant openings 12 to furnish that degree of flexibility which is necessary to permit the device to be sprung open for application to the sole, yet readily to be closed in upon and to embrace the sole edge.

This device gives approximate shape to 65 the textile shield and also gives a certain

firmness or rigidity to the device to permit more ready and convenient handling thereof. It is preferably used in connection with the textile shield, giving added protection to the sole edge, although it is not necessary 70 that two be always conjointly used.

Claims:

1. A fore-part sole edge protector comprising a pliable shield having a top edge engaging portion, and means within the 75 limits of the fore-part thereof to tension the same in position encompassing the sole edge.

2. A fore-part sole edge protector comprising a textile shield having a top edge engaging portion, and means within the 80 limits of the fore-part thereof to tension the same in position encompassing the sole edge.

3. A fore-part sole edge protector comprising a pliable shield having a top edge engaging portion constructed to cover the sole 85 edge and top edge face thereof, and retaining means therefor within the limits of the fore-part thereof.

4. A fore-part sole edge protector comprising a pliable shield, and means within 90 the limit of the fore-part to stretch it across the sole bottom.

5. A sole edge protector comprising a laterally expansible shield to encompass the fore part sole edge, and heel engaging retaining means therefor. 95

6. A sole edge protector comprising a laterally expansible shield to encompass the fore part sole edge, heel engaging and retaining means therefor, and heel rand protecting and engaging means therefor. 100

7. A shoe sole edge protector comprising a shield shaped to encompass the forepart sole edge and means connected with said shield to engage the heel and draw the shank 105 ends of said shield in diagonal directions to hold it closely on to the sole edge.

8. A protector of the character described comprising a shield having a part constructed to enter the rand crease of a shoe, 110 said shield being shaped to protect the upper and side faces of the heel rand, and retaining means for said shield.

9. A protector of the character described comprising a shield having a part constructed to enter the rand crease of a shoe, 115 said shield being shaped to protect the upper and side faces of the heel rand, and yielding retaining means for said shield.

10. A protector of the character described comprising a shield having a part constructed to enter the rand crease of a shoe, 120 said shield being shaped to protect the upper and side faces of the heel rand, and means constructed for engagement with the 125 forepart of the shoe to retain said shield in position.

11. A sole edge protector comprising a fore part sole edge shield, and a heel shield separable therefrom and elastically con- 130

nected thereto to enable each to contribute to the retention of the other in position.

12. A sole edge protector comprising a resilient outer sole edge shield, and pliable 5 detachable retaining means therefor.

13. A sole edge protector comprising a resilient outer sole edge shield, and detachable retaining means therefor.

14. A fore-part sole edge protector comprising a sole edge shield provided with a top edge protecting portion, and means to draw the latter toward the bottom of the crease between the upper and sole.

15. A protector of the character described comprising a shield shaped to protect the top, side and bottom faces of the margin of a shoe sole, means for tensioning said shield across the bottom of said sole, and means acting yieldingly to draw said shield over

the upper face of the sole margin toward the 20 upper of the shoe.

16. A protector of the character described comprising a pliable shield member and a resilient shield member supporting said pliable member, said members being shaped 25 to protect the top, side and bottom faces of the margin of a shoe sole and having an aperture formed therethrough near the central portion of the part that covers the shoe bottom.

In testimony whereof, I have signed my name to this specification, in the presence of two subscribing witnesses.

THOMAS G. PLANT.
